UNITED STATES PATENT OFFICE.

JOHN W. STOKES, OF DALLAS, TEXAS.

INCINERATOR.

Application filed May 7, 1925. Serial No. 28,533.

To all whom it may concern:

Be it known that I, JOHN W. STOKES, citizen of the United States of America, residing at Dallas, in the county of Dallas and 5 State of Texas, have invented certain new and useful Improvements in Incinerators, of which the following is a specification.

This invention relates to new and useful improvements in incinerators.

10 The object of the invention is to provide an incinerator particularly adapted for burning garbage, trash and the like in an expeditious and efficient manner.

A particular object of the invention is to 15 utilize the products of combustion to the fullest extent in the main combustion or burning chamber so as to generate an intense heat and whereby wet as well as dry matter may be consumed.

20 Another object is to recirculate a portion of the hot gases passing from the burning chamber, whereby a more intense heat and a more perfect combustion is obtained in the burning chamber.

25 A further object is to provide an auxiliary combustion chamber having a grate adjacent the outlet duct of the burning chamber, whereby an intense fire may be maintained for burning and melting cans and other matter difficult to consume; together with means 30 for preventing the articles from being drawn from the grate into the flue and stack.

A still further object is to provide an incinerator having a down-draft cross flue extending under the burning chamber to a 35 stack on the opposite side, whereby the products of combustion are carried under the burning chamber, and portions admitted to the top burning chamber.

40 A particular object is to eliminate the usual baffle wall found in the burning chambers of most incinerators; whereby all grates in the burning chamber are made more accessible and the matter to be burned may 45 be more readily handled.

Another object of the invention is to provide an ash conveyor and a grate thereover, whereby the ashes may be raked from the pits and readily disposed of.

50 A construction designed to carry out the invention will be hereinafter described together with other features of the invention.

The invention will be more readily understood from a reading of the following specification and by reference to the accompany-

ing drawings, in which an example of the invention is shown, and wherein:

Fig. 1 is a horizontal cross-sectional view on the line 1—1 of Fig. 2,

Fig. 2 is a transverse vertical sectional view on the line 2—2 of Fig. 1,

Fig. 3 is a transverse vertical sectional view on the line 3—3 of Fig. 1,

Fig. 4 is a reduced horizontal cross-sectional view on the line 4—4 of Fig. 3,

Fig. 5 is a reduced plan view,

Fig. 6 is an enlarged cross-sectional view on the line 6—6 of Fig. 5, and

Fig. 7 is a vertical sectional view on the line 7—7 of Fig. 2.

In the drawings the numeral 10 designates the front wall, 11 the back wall, 12 the right side wall and 13 the left side wall of the main burning or combustion chamber of the incinerator. Within the chamber is an elevated floor 14 in which side grates 15 preferably of the rocker type, and a center grate 16, are set substantially flush. The burning chamber has an arch 17 spanning from the front to the back wall. An air space 18 is provided above the arch under a floor 19. Charging hoppers 20 mounted in the floor 19 extend through the arch so as to discharge onto the grates. Each hopper has a suitable closure 21.

Fire doors 22 are provided in the front wall (Figs. 1 and 2) for the grates and under these doors, ash doors 23 are arranged for raking out the ashes from the pits 24 under said grates. In the wall 13 a duct 25 extends upwardly from the floor 14 near the center of said wall. This duct forms the outlet from the main combustion chamber to an auxiliary burning or combustion chamber 26 built along the outer side of the wall 13. The arch 17 is extended over the chamber 26. Contiguous to the bottom of the duct 25 a grate 28 is arranged in a floor 28' at the same level as the floor 14. Access to the grate 28 is had by a door 29. In order that cans, papers, rags and other articles reaching the grate 28, may not pass into a down draft compartment or chamber 26' in rear of the chamber 26, I mount an upright grille 30 extending transversely of the chamber from the grate 28 to the arch, which grille forms a perforate division wall or partition between said chambers 26 and 26'.

The chamber 26 has an ash pit 31 under the grate and this pit has a floor 31' which

inclines rearwardly through an arch 30' under the grille 30. A door 29' in the front wall gives access to the ash pit (Fig. 3). A tunnel or transverse flue 32 extends from the bottom of the compartment 26' through the wall 13 and under the floor 14 in rear of the grates 15 and 16. This flue connects with a smoke stack 33 by means of an angle duct 33'. The stack is built in spaced relation to the walls of the incinerator and may be attached to the walls 34 of the incinerator house. The stack has a damper 35 above the entrance of the duct 33'. The products from the burning chamber pass through the duct 25, chamber 26, grille 30 and chamber 26' to the flue 32, duct 33' and thence to the stack 33; this produces a down draft between chamber 26 and flue 32 via chamber 26', which has many advantages in an incinerator.

Within the main burning chamber I mount against the back wall 11 upright flues 36 terminating at the arched roof 17 and extending through the floor down into the flue 32 at the rear side thereof. These flues 36 have vertical openings 38 in the flue 32 and wings or baffle walls 37 extend transversely of the flue 32 from said openings. The baffles extend from the bottom to the top of the flue 32 and have their outer edges terminating at the central portion of said flue 32. It will be noted that the baffle walls are set at an angle and directed toward the entrance to the flue 32. By this arrangement a portion of the hot air currents and gases passing through the flue 32 are deflected into the openings 38, while the main body of the same passes through the flue to the stack 33.

The hot air currents and gases which are deflected into the flues 36 are drawn up into the main burning chamber and recirculated in said chamber and thus increase the heat and promote combustion. The suction created by the stack 33 will not affect the upward passage of currents through the flue 36, owing to the baffle walls 37. The duct 25 is amply large to induce a free escape of the products.

One of the important features of the invention is an ash conveyor screw 39 disposed in a trough 40 in front of the ash pit doors 23 and 29'. This trough and screw are covered by a plate 41 having openings or grates 42 therein at the doors. The conveyor screw and trough extend to a suitable discharge point at which an elevator or other disposal means (not shown) may be located. The conveyor is suitably driven. It is merely necessary to rake the ashes from the pits onto the plate at the grates 42, through which the ashes fall into the conveyor trough.

In operating the incinerator a fire is built on the right hand (Fig 1) grate 15 in a suit-

able manner and the garbage and refuse is dumped through the hoppers 20. The garbage and refuse are raked onto the grates 15 and 16 and a bed of fire built up in the burning chamber. Cans and other slow burning matter are raked or pushed through the duct 25 onto the grate 28, where the heat is most intense. The products of combustion pass through the grille 30 into the chamber 26', from which they are drawn by suction from the stack 33, through the flue 32. A portion of the hot gases will pass up the flues 36 and will be discharged into the top of the burning chamber, thus being recirculated and intensifying the heat therein. By means of the damper 34 the draft may be controlled. The ashes are raked from the pits 24 and 31 onto the grates 42 and deposited in the trough 40 from which they are conveyed by the screw 39.

Various changes in the size and shape of the different parts, as well as modifications and alterations may be made within the scope of the appended claims.

What I claim, is:

1. In an incinerator, the combination of a main combustion chamber having a plurality of spaced transversely alined grates, an auxiliary combustion chamber separate from said main combustion chamber and disposed at one side thereof and parallel therewith, a grate in the auxiliary combustion chamber disposed in alinement with the grates in the main combustion chamber, a wall between said chambers having a restricted flue passage connecting the said chambers for the flow of the flames and products of combustion across the main combustion chamber and laterally into the auxiliary combustion chamber, a transversely extending horizontal flue beneath the floor of the main combustion chamber in rear of the line of the grates, a downdraft flue leading to one end of said passage from the auxiliary combustion chamber in rear of the grate therein, a stack in communication with the opposite end of said flue, and vertical return flues communicating with the horizontal flue between the downdraft flue and outlet to the stack and leading from said horizontal flue to the top of the main combustion chamber.

2. In an incinerator, the combination of a main combustion chamber having a plurality of spaced transversely alined grates, an auxiliary combustion chamber separate from said main combustion chamber and disposed at one side thereof and parallel therewith, a grate in the auxiliary combustion chamber disposed in transverse alinement with the grates in the main combustion chamber, a wall between said chambers having a restricted flue passage connecting the adjacent sides thereof for the flow of the flames and products of combustion

across the main combustion chamber and laterally into the auxiliary combustion chamber, a transversely extending horizontal flue beneath the floor of the main combustion chamber in rear of the line of the grates, a downdraft flue leading to one end of said passage from the auxiliary combustion chamber in rear of the grate therein, a stack disposed in communication with the opposite end of 10 said flue, vertical return flues communicating with the horizontal flue at a point between the downdraft flue and the stack and leading from said horizontal flue to the top of the main combustion chamber, and baffles 15 at the inlet ends of said return flues projecting into the horizontal flue at an angle thereto and in the direction toward said downdraft flue.

3. In an incinerator, the combination of a 20 main combustion chamber having a plurality of spaced transversely aligned grates, an auxiliary combustion chamber separate from said main combustion chamber and disposed at one side thereof and parallel therewith, 25 a grate in the auxiliary combustion chamber disposed in transverse alignment with the grates in the main combustion chamber, a wall interposed between said chambers and having a restricted duct in line with the grates, said wall closing communication 30 with said chambers except through said duct, a downdraft flue leading from the auxiliary combustion chamber in rear of the grate therein, a stack disposed in rear of the main combustion chamber and at the 35 side thereof opposite the auxiliary combustion chamber, a horizontal transverse flue arranged beneath and in rear of the main combustion chamber and in advance of the stack, said flue communicating at one end with said downdraft flue, a discharge duct extending at an angle to said horizontal flue between the outlet end thereof and the stack, vertical return flues disposed between the inlet end of the horizontal flue 40 and the discharge duct and leading from the rear side of said flue to the top of the main combustion chambers, and baffles at the inlet ends of the return flues extending into the horizontal flue at an angle in the direction toward the inlet end of said horizontal flue. 45

50

In testimony whereof I affix my signature.

JOHN W. STOKES.
